UNITED STATES PATENT OFFICE.

WALTER HAHNEMANN, OF KITZEBERG, NEAR KIEL, AND WILHELM RUDOLPH, OF KIEL, GERMANY, ASSIGNORS TO THE FIRM: SIGNAL GESELLSCHAFT M. B. H., OF KIEL, WERK RAVENSBERG, GERMANY.

MEANS FOR MOUNTING DIAPHRAGMS.

Application filed August 25, 1921. Serial No. 495,231.

To all whom it may concern:

Be it known that we, WALTER HAHNEMANN and WILHELM RUDOLPH, citizens of the German Republic, and residing at Kitzeberg, near Kiel, and at Kiel, county of Schleswig-Holstein, State of Prussia, Germany, have invented certain new and useful Improvements in Means for Mounting Diaphragms, of which the following is a specification.

The invention relates to sound apparatus of the kind provided with a diaphragm for transmitting or collecting sound waves.

In sound apparatus of this type difficulty is experienced in mounting the diaphragm in the casing surrounding the actual apparatus so that on the one hand it completely closes the casing tightly, a requirement which is particularly important with submarine sound apparatus, and on the other hand so that it does not bend and that it maintains a uniform tension.

Hitherto for this purpose two methods have chiefly been employed, viz, either soldering the diaphragm in the edge of the casing or securing it by means of screws.

The soldering method has the great disadvantage that the tension of the diaphragm is altered during soldering so that it is impossible with different apparatus to make the tension and thus also the tuning of the diaphragm quite equal. Furthermore, the diaphragm also gradually becomes loose in the soldered joint when strong pressures are exerted upon it so that its tension does not remain constant. The same drawback occurs also with diaphragms secured by screws. In addition, in this latter case, it is only possible with difficulty to seal the diaphragm uniformly tight because between every two screws there are always relatively loose places.

The object of the invention is to remove these drawbacks. It consists in the feature that the diaphragm is embraced by means of a shrunk ring or a structure acting in the manner of a shrunk ring and sealed tight.

Sometimes it occurs that the pressure of the shrunk ring becomes too great and the casing itself as a whole is narrowed or compressed by this pressure. In consequence of that the diaphragm is bent and its tuning changed. According to the invention the

outer part of the casing adjacent the ring is shaped in conical form or tapered so that the ring is allowed to slide during contracting to a narrower place of the casing. Another method of preventing the casing from being narrowed consists in thickening the casing at the zone where the pressure of the ring acts.

Figs. 1 to 4 show examples of the invention, all figures being sections through sound receiving apparatus with diaphragms mounted in accordance with the invention or through parts of apparatus of this kind.

In Fig. 1 *a* is a casing enclosing the detector. The upper edge *b* of the casing *a* forms a shoulder thereon. The diaphragm *c* has a marginal portion bent over at right angles to form a flange, and is mounted on the edge *b* of the case *a* where it is firmly pressed against the edge *b* by a ring *d* the conformation of which corresponds to the conformation of the edge *b*. Between the ring *d* and the edge of the casing a slot *e* remains free so that the ring *d* only rests on the diaphragm *c*. The ring *d* is provided at *f* with a recess in order to prevent the diaphragm *c* from being strained. The diaphragm *c* carries at its centre the microphone *g* located in the interior of the case *a*. *h* is a tension ring adapted to be screwed against the diaphragm in order to regulate the tuning of the latter.

The method of mounting the diaphragm is as follows: The diaphragm *c* is pressed from annealed sheet in the prescribed form and placed over the edge of the case. The ring *d* is then heated, placed over the diaphragm *c* and pressed thereon from above by means of a weight. On cooling, the ring contracts and radially presses the diaphragm firmly on the edge *b* of the casing. When the weight is removed the cooled ring remains in the position to which it has been pressed by the weight. In this manner it is assured that the diaphragm is firmly pressed not only radially but also from the top on the edge of the casing so that there is formed by the ring a uniform edge engagement from which the diaphragm oscillates.

In Fig. 2 a modified constructional form of the invention is represented. The reference characters correspond to those of Fig. 1. In this case the casing or the case *a*

itself acts as shrunk ring. The casing *a* is heated and embraces the diaphragm *c* so that on cooling the casing the diaphragm is firmly pressed between the latter and the ring *d*.

In Fig. 3 another modification of the invention is shown in which the outer part of the casing adjacent the shrunk ring has a conical form or tapers inwardly, the upper portion of this part being wider than the lower portion. In contracting the ring slides or is caused to slide by forcing it toward the narrower portion.

In Fig. 4 the part of the casing adjacent the shrunk ring is much thicker than the other parts of the wall of the casing. The other reference characters in Figs. 3 and 4 are the same as in Figs. 1 and 2.

In the examples of Figs. 3 and 4 still another characteristic feature of the invention is represented consisting of an annular border arising from the top face of the casing. This border serves to stretch the diaphragm.

In order in given cases to avoid any straining of the diaphragm on the shrinking of the ring, it is preferably mounted hot after it is adjusted in its width so that in the hot condition it fits exactly.

We claim:—

30 1. In a sound apparatus, the combination with the casing of the apparatus, of a ring, and a diaphragm having a marginal portion interposed between the ring and casing and held tight by a clamping effect exerted by the shrinkage of one of the said parts between which it is interposed.

40 2. In a sound apparatus, the combination with the casing of the apparatus, of a ring, and a diaphragm having a marginal portion interposed between the ring and the casing and held tight by a clamping effect exerted by the shrinkage of the ring, the

ring being adapted to seal the joint between the margin of the diaphragm and the casing.

3. In a sound apparatus, the combination with the casing of the apparatus, of a ring, and a diaphragm having a marginal portion interposed between the ring and casing and held tight by a clamping effect exerted by the shrinkage of one of the said parts between which it is interposed, the part of the wall of the casing adjacent the shrunk ring being considerably thicker than the other parts of the wall.

4. In a sound apparatus, the combination with the casing of the apparatus, of a ring, and a diaphragm having a marginal portion interposed between the ring and casing and held tight by a clamping effect exerted by the shrinkage of one of the said parts between which it is interposed, and an annular border on the top face of the casing engaging the diaphragm.

5. The method of mounting and fastening an oscillatory diaphragm on the casing of a sound apparatus, consisting in bending a marginal portion of the diaphragm to form a flange, fitting the flange over the edge of the casing, fitting a ring over said flange, and shrinking the ring in place so as to press the flange tightly against the casing.

6. The method of mounting and sealing an oscillatory diaphragm on the casing of a sound apparatus, consisting in bending a marginal portion of the diaphragm to form a flange, fitting it over the edge of the casing, heating a ring and fitting it over said flange, and shrinking the ring in place so as to press the flange tightly against the casing.

In testimony whereof we affix our signatures.

WALTER HAHNEMANN.
WILHELM RUDOLPH.
